Attorneys

UNITED STATES PATENT OFFICE.

JOSEPH F. KISCH, OF OMAHA, NEBRASKA, ASSIGNOR OF ONE-HALF TO ANTON L. KISH,
OF OMAHA, NEBRASKA.

ORNAMENTAL BOX.

1,260,912.

Specification of Letters Patent. Patented Mar. 26, 1918.

Application filed April 16, 1917. Serial No. 162,451.

To all whom it may concern:

Be it known that I, JOSEPH F. KISCH, a citizen of the United States, residing at Omaha, in the county of Douglas and State 5 of Nebraska, have invented certain new and useful Improvements in Ornamental Boxes; and I do hereby declare the following to be a full, clear, and exact description of the invention, such as will enable others skilled 10 in the art to which it appertains to make and use the same.

This invention relates to ornamental devices and more particularly to ornamental receptacles.

15 It is one of the objects of the present invention to provide an improvement in the construction of ornamental receptacles, such for instance as pin trays or button boxes or jewelry boxes, etc., and it is the particular object of the present invention to provide an ornamental receptacle in which the sides or outer members thereof are formed 20 of transparent material, preferably glass, and it is an object of the invention to securely fasten the glass sections or members 25 forming the receptacle in such a manner as to effectually cover the joint formed by the abutting edges of the glass panels or sections, and at the same time provide for the 30 utilization of the joint-forming means in a manner to cover the line of juncture between the sections and at the same time securely fasten the sections together, and also to provide a joint-forming means which serves 35 the function and purpose of forming a border around the marginal portion of the glass or transparent receptacle wall members or sections.

40 A further object of the present invention is to provide an ornamental receptacle or box and to so construct and arrange the binding elements of the members of the receptacle or box so that the edges of the binding means may be effectually covered so as 45 to conceal the irregular exposed edges of the binding means and at the same time obtain an ornamental frame around the marginal portions of the sections in combination with the binding means which latter 50 form a border substantially concentric to the inner ornamenting frame.

Another object of the present invention 55 is to improve the construction of receptacles having relatively hinged members so as to not only provide for the relative movement

of the members one to the other, but also to form an ornamental connection which serves as a hinge for the two members, and which hinge further involves a covering means for the joint between the members 60 hinged together.

With these and other objects in view, as will be rendered manifest in the following specification, there is illustrated in the accompanying drawing one embodiment of the 65 invention, in which:

Figure 1 shows the invention as embodied in a receptacle in the form of a tray having transparent side members.

Fig. 2 is a sectional detail view illustrating the joint-forming means and the ornamenting frames as employed in the receptacle.

Fig. 3 is a perspective view of the invention as it is embodied in the form of a box 75 having a receiving chamber and a cover hinged thereto.

Fig. 4 is a perspective showing a fragment of the box and hinged cover member and showing in detail the hinge construction uniting these members.

The present invention contemplates the provision of a receptacle of various forms as above indicated, as for instance, the provision of an ornamental tray having transparent sides, and also the invention may be embodied in the form of boxes or receptacles with movable or removable covers, and in the form of the invention illustrated in Fig. 1, the receptacle is depicted as a tray 90 having an octagonal bottom 2 with a suitable number of marginal upturned sections 3, the bottom and sections preferably being made of glass or other transparent material, the bottom in the present invention being 95 in the form of a mirror and the sides and upwardly directed members 3 of the tray being made of glass of different colors or surface finish, such for instance, as may be obtained by grinding or chipping.

100 An important feature of my present invention resides in the means whereby a very ornamental and attractive receptacle is obtained and this feature comprises the provision of means for bordering and binding 105 the several sections of the receptacle together in a neat and attractive manner so that the joints between the abutting edges of the several sections 2 and 3 for instance going to compose a receptacle are concealed, 110

and at the same time effectually united as to produce a substantial frame or box. To that end, in the various adaptations of receptacles in which the invention may be utilized, the section members 3 are shown as assembled into proper relation so as to bring the contiguous edges into abutment as shown in Fig. 2, and these abutting edges are then bound together on the outer surfaces of each 10 of the members by the application thereto of a suitable binding strip or medium 4 which may be of paper, cloth or other pliable material, preferably pasted on its inner surface to the outer surface of the adjacent 15 section members 2 and 3 at the joint 5, the binding means preferably being formed of a strip or tape of suitable width and material sufficiently strong so as to effectually secure the pieces in assembled relation. 20 Upon the inner surface of the tray as illustrated in Figs. 1 and 2, and at the joint 5 there is applied an inner binding strip or means 6 of suitable material, and obviously the inner binding strip 6 and the outer 25 binding strip 4 may be of any suitable color or decorated in any suitable manner so that when the binding is extended continuously around the joint at 5 connecting the bottom 2 to the several upwardly and angularly disposed members 3, the inner binding strip 6 will form a continuous border, the exposed surface of which appropriately ornaments the receptacle. To secure further ornamentation of the device and also for the 30 purpose of covering the edges of the binding and bordering strips 4 and 6, for instance, there may be applied to these edges in the positions where they overlie the surface of the members 2 or 3, an ornamenting 35 device in the form of lace paper for instance, or other suitable ornamenting means as indicated at 7, the several strips of ornamenting material 7 forming, when applied to the border edges 6 of one of the panels 40 8 for instance, a complete frame through which the rays of light may pass through the transparent or glass panels 3. In a like manner the edges of the binding strip or tape 4 may also be covered with a frame 45 strip 7 of suitable design and ornamentation, it obviously being possible to utilize a different ornamenting strip 7 on the outside of the tray than that which is used on the inside of the tray. The marginal and 50 outer rim-forming edges of the several members 3 of which the tray is composed in Fig. 1 are adapted to be covered by a suitable binding and bordering strip as indicated at 55 8 in Fig. 2 in the detail section, this strip 60 being of such width as to be folded from overlapping relation upon the inner surface of a section 3, for instance, over the outer edge 9 of the glass plate or panel 3, and then folded inwardly underneath of this 65 panel and appropriately secured thereto,

thus covering the exposed rim or edge of the section 3, and the edges of the bordering strip 8 are covered with the border strip or frame 7 as above described as utilized to cover the binding strip 6 which secures the 70 bottom 2 of the tray to the lower portions of the panel members 3.

There is shown in Fig. 3 a box or receptacle, for instance in the form of a jewelry box, in which my present invention is 75 utilized in the form of glass panels 3 which are applied to an inner shell or body 10 of the box, this shell or body 10 being constructed of any suitable material, such for instance, paste board, and to secure the panels 3 to the shell 10. The bordering strip 4^a is applied along the marginal outer surface of the panel 3 to be secured in place and is then turned inwardly over the top or rim edge as at 12 of a panel, and then secured to the 80 adjacent and outer face of the inner shell as at 13. The corners of contiguous panels or sections 3 of the box are shown as bound together by a piece of binding strip as illustrated at 4^b which is bent around the angular corners of the juncture of the end and front panels, for instance, the end binding means or strip 4^b at each of the corners of the box being carried down to the bottom of the box where it intersects with the bottom 85 binding strip applied as above indicated to the front marginal portion of each panel or glass section 3. To cover the edges of the binding strip 4^a or 4^b of the different panels 3 of the box, there may be applied to the face 90 of these panels a framing strip as above indicated, as illustrated at 7, Fig. 3. The portion of the bordering strip 4^a where it is applied to the shell 10 may be concealed or covered by suitable lining material as 100 illustrated at 4^c for instance, this lining being utilized to cover the interior of the shell and also the rim or top edge thereof so that there will be a harmonious interior 105 finish to the box and its relative interior 110 parts.

Another important feature of my present invention resides in the provision of any ornamenting means which may be interposed between the shell and the side transparent 115 panels 3 or may be applied to or formed upon the rear or inner face of each or any of the sections 3 so that in the finished box, the ornamental or other media introduced between the outer transparent panels or 120 sections 3 and the inner construction of the box, may be plainly viewed from the outside, the whole resulting in a very neat, attractive and highly ornamental article. As illustrated, in an ornamental box of this 125 type there may be introduced between the panels 3 and the inner construction of the box, a picture as illustrated in Fig. 3 which is placed upon a suitable back-ground of paper, for instance, of suitable color, al- 130

though it is to be understood that the ornamenting device, arranged in the rear of a transparent member 3 may be in the form of any suitable picture or any suitable means for displaying to view, the desired feature which may be arranged behind the glass sections 3, as for instance, postal cards or various fabrics or other media.

In Fig. 4 there is illustrated the provision of the hinge by which the cover 15 of the box is hinged to the lower structure thereof, and this hinge construction involves the application to the members which are to be hinged together, of a front or inner flexible strip of material 16 which may be fabric or other pliable material, the central portion of which is secured at 17 to the adjacent and parallel edges 18 of the coplanar members which are connected by the hinged strip 16. In addition to the inner covering

strip 16 there is applied to the rear surface of the hinged members of the top and bottom of the box a further hinge strip as illustrated at 19 on the outer or rear side of these members, this strip being applied to the marginal adjacent portions of the box members as shown and the edges of the hinge strip 19 may be covered by a frame strip 7^a if desired.

What I claim is:—

An ornamental receptacle comprising an inner shell or box, outer transparent wall sections for the box, a framing strip-like means overlapping the marginal portion of the front of the walls and securing the adjacent edges of each together and also securing the sections to the box's outer surface.

In testimony whereof I affix my signature.
JOSEPH F. KISCH.
